**PORABLE MOTOR DRIVEN ROTARY BRUSH FOR
CLEANING WALLS, FLOORS OR THE LIKE**

Roland A. Aaker, Minneapolis, Minn., assignor to Aire-
Scrub Corporation, Minneapolis, Minn., a corporation
of Minnesota

Filed Mar. 2, 1965, Ser. No. 84,038

Term of patent 14 years

(Cl. D9—2)

Fig. 3.

Fig. 4.

Fig. 5.

FIG. 1 is a side elevational view of a portable motor driven rotary brush for cleaning walls, floors or the like, showing my design;

FIG. 2 is a rear elevational view of the same;

FIG. 3 is a front elevational view of the same;

FIG. 4 is a bottom plan view of the same;

FIG. 5 is a top plan view of the same;

The side opposite that shown in FIG. 1 is substantially a mirror image thereof.

I claim:

The ornamental design for a portable motor driven

rotary brush for cleaning walls, floors or the like, as shown and described.
